UNITED STATES PATENT OFFICE.

FRANK F. RIGGS, OF LEAD, SOUTH DAKOTA.

DUST-COLLECTOR FOR DRILLS.

1,181,925.

Specification of Letters Patent.

Patented May 2, 1916.

Application filed January 8, 1916. Serial No. 71,029.

To all whom it may concern:

Be it known that I, FRANK F. RIGGS, a citizen of the United States, residing at Lead, in the county of Lawrence and State 5 of South Dakota, have invented certain new and useful Improvements in Dust-Collectors for Drills, of which the following is a specification.

This invention relates to devices employed 10 for collecting the dust and like particles of material which arise from the working of drills, more particularly of pneumatic drills, and has for one of its objects to simplify and improve the construction and increase the 15 efficiency and utility of devices of this character.

Another object of the invention is to provide a device of this character which may be applied without material structural change 20 to drills and like devices of various sizes and employed for various purposes.

The improved device is more particularly applicable to drills employed in stone quarries and the like, and likewise employed in 25 dressing and working building stone and for like purposes where the operation of the drill produces quantities of fine dust or pulverized material which is liable to annoy or injure the workmen, and for the purpose of 30 illustration the improved device is shown applied to a conventional pneumatic drill, but it is to be understood that it is not desired to limit the invention in any particular in this respect.

35 In the drawings employed for illustrating the preferred embodiment of the invention Figure 1 is a side elevation of a conventional pneumatic drill with the improvement applied; Fig. 2 is an enlarged plan view with the top removed and with the drill stock in 40 section on the line 2—2 of Fig. 1; Fig. 3 is a section on the line 3—3 of Fig. 2 with the cover in place thereon; Fig. 4 is a section on the line 4—4 of Fig. 2 with the cover in place 45 thereon.

Corresponding and like parts are referred to in the following description and indicated in all the views of the drawings by the same reference characters.

50 The improved device comprises a hollow body 10, preferably cylindrical and with oppositely disposed lateral lugs 11 having threaded apertures and arranged to receive corresponding lateral lugs 12 projecting

from a top or closure 13 for the body. The 55 lugs 12 are perforated to receive clamp screws 14 which enter the threaded apertures of the lugs 11 and thus secure the closure 13 in place. The closure 13 is provided with a central aperture 15 through which 60 the stock 16 of the drill operates. The bottom of the body 10 is annular, or with a relatively large opening 18, so that a considerable space is left between the stock 16 and the walls of the opening 18 for the free passage 65 of the dust and like matter. The body 10 is formed with a channel 19 which slopes constantly downwardly toward one side and merges into a pocket or recess 20 at the lowest point of the channel. The bottom of the 70 recess is preferably located a considerable distance below the lower line of the lowest point of the channel, and communicating with the recess 20 is a lateral discharge passage 21 leading outwardly from the body. 75 Any suitable conductor may be attached to the outlet 21, but as this conductor forms no part of the present invention it is not deemed necessary to illustrate the same. The bottom of the body is designed to rest upon 80 the stone or other material through which the drill is operating and indicated conventionally at 22, and a rubber or other packing 23 may be employed between the body 10 and the rock or other material 22 to prevent 85 the escape of dust between the body and the rock.

A packing washer 24 of leather or like material may be placed upon the top 13 and surrounding the drill rod 16, and held in 90 place by an annular holding member or washer 25, the latter being secured by clamp bolts or like devices 26.

The improved device is simple in construction, can be inexpensively manufactured, preferably of cast metal, and may be readily applied to drill stocks of various sizes by slight and unimportant modifications of the opening 15 of the cover 13.

Having thus described the invention, what 100 is claimed as new is:—

1. In a device of the class described, a hollow body having a lateral discharge, a top having an aperture to receive a drill stock, and a bottom having an opening, said 105 bottom having a channel surrounding its opening and constantly sloping toward the discharge and communicating therewith and

said discharge located below the line of the channel.

2. In a device of the class described, a hollow body including a top and a bottom, the bottom having an opening having a channel surrounding the opening and sloping constantly to one side and a recess into which

the channel merges at its lowest point, said body having a lateral discharge communicating with the recess and said top having 10 an aperture to receive a drill stock.

In testimony whereof I affix my signature.

FRANK F. RIGGS. [L. S.]
